John Conn, Inventor
By his Attorney, Wm. J. Bates.

UNITED STATES PATENT OFFICE.

JOHN CONN, OF VALPARAISO, INDIANA.

NURSERY AND SEWING TABLE.

SPECIFICATION forming part of Letters Patent No. 361,267, dated April 19, 1887.

Application filed January 22, 1887. Serial No. 225,075. (No model.)

To all whom it may concern:

Be it known that I, JOHN CONN, a citizen of the United States, residing at Valparaiso, in the county of Porter and State of Indiana, 5 have invented certain new and useful Improvements in Nursery and Sewing Tables; and I do hereby declare the following to be a full, clear, and exact description of the invention, such as will enable others skilled in the 10 art to which it appertains to make and use the same.

This invention relates to that class of tables which is particularly adapted for nursery, sewing, and other purposes; and with these ends 15 in view the invention consists in the novel construction and arrangement of parts, as will be hereinafter more particularly described, and specifically pointed out in the claims.

In the accompanying drawings, to which 20 reference is had, and which fully illustrate my invention, Figure 1 is a side elevation of my improved table. Fig. 2 is a longitudinal vertical section of the same; and Fig. 3 is a plan or top view of the table, illustrating more fully 25 the work-holder and its attachments.

The letter A represents a stand of ordinary construction, provided with the usual legs, *a a a*, secured to the lower part thereof in any suitable manner. This stand or support at 30 its top terminates in annular bearings B and B', the bearing B' supporting loosely a hub, b, which carries a revolving wheel or clothes-hanger, the spokes C of which are tenoned therein in the usual manner at their inner and 35 larger ends, and upon their outer ends is secured a rim, D, of wire or strap metal, if preferred, by means of staples *d*.

Mounted upon the top of the stand A is a table, E, which may revolve or be permanently 40 secured to said stand by means of a screw, *e*. Upon the under side of this table is a strip, G, of wood or any suitable material, the strip being securely fastened to the table by means of screws or similar fastenings. This strip G 45 has a hole bored in the center, within which fits a projection or extension, *b*, of the stand A, the table E receiving its support from the projection or extension *b* and annular bearing B, and which, if desired, may revolve thereon. 50 In the center of the table E is a receptacle, H, which in this example is circular, but may be of any desired form. Within this recep-

tacle H is detachably secured a lamp, I, by means of V-shaped springs *h*, the lower ends of which fit in holes in the periphery of the receptacle, and the springs themselves pass through kerfs *h'*, made in the periphery of the receptacle, the V-shaped points of the springs extending over the top of the periphery and embracing the base of the lamp, which holds 55 the lamp I rigidly and snugly in place within the receptacle H. When necessary to remove the lamp, as occasion will require at times, it will be only necessary to pull the springs back 60 out of contact with the base of the lamp, and 65 the lamp is immediately released, and can be taken out of the receptacle.

To the table E is hinged a fly-leaf by means of hinges *i*, and when in its closed or normal position abuts against the strip G, which forms 70 a support therefor, this fly-leaf being shown raised in Fig. 2.

The letter K represents a bifurcated detachable spring-holder, which in form describes the arc of a circle, the ends of which terminate in eyes or sockets *k*, through which pass detachable fastening-pins L, the lower ends of which passing in holes *l*, made in the table, which securely but detachably fastens the holder to the table, the upper portion of these pins 80 forming cushions K' for pins, needles, &c.

To the inner curved spring of the bifurcated spring work-holder, and in the center thereof, is a receptacle, M, the purpose of which is for holding matches or other convenient articles. 85 This receptacle is soldered or otherwise secured to a plate, N, which holds sand-paper for striking matches thereon or for other suitable purposes. This plate N is in turn soldered to the center and inner curved spring of the 90 bifurcated holder. Arranged to form the arc of a circle similar to the spring-holder is a plurality of pins, *n*, placed equidistant apart, and which are adapted to hold spools of cotton, &c.

The convenience and assistance attending the construction of my table to the user will be obvious from the foregoing description, while at the same time it is cheaply manufactured, and requires but little space in transportation.

Having thus described my invention, what I claim as new, and desire to secure by Letters Patent, is—

1. The combination, with the stand A, of the revolving hanger for clothes, the table E, provided with the receptacle H, having the kerfs therein for holding the V-shaped springs, 5 and the V-shaped springs h, for holding the lamp within the receptacle, all arranged and operated as herein described.

2. The combination, with the stand and revolving hanger, of the table having the workholder detachably secured thereto by means of pins, and sockets formed in the holder, the

upper portions of the pins serving as needle or pin cushions, and a plurality of pins for holding spools, all arranged and operated as herein set forth.

In testimony whereof I affix my signature in presence of two witnesses.

JOHN CONN.
